[57] CLAIM

The ornamental design for a handle for a saw blade, as shown and described.

DESCRIPTION

FIG. 1 is a side elevational view of a handle for a saw blade incorporating my new design with the saw blade illustrated in phantom line for illustrative purposes only; FIG. 2 is a side elevational view of the handle of my new design and drawn to an enlarged scale;

FIG. 3 is a bottom view thereof;

FIG. 4 is a top view thereof;

FIG. 5 is a front elevational view thereof; and

FIG. 6 is a rear elevational view thereof.
